UNITED STATES PATENT OFFICE.

DANIEL DOLHAY, OF LEECHBURG, PENNSYLVANIA.

OPERATING MECHANISM FOR FANS.

1,195,788.

Specification of Letters Patent.

Patented Aug. 22, 1916.

Application filed April 4, 1916. Serial No. 38,884.

To all whom it may concern:

Be it known that I, DANIEL DOLHAY, a subject of the King of Hungary, residing at Leechburg, in the county of Armstrong and State of Pennsylvania, have invented certain new and useful Improvements in Operating Mechanism for Fans, of which the following is a specification.

This invention relates to new and useful improvements in operating mechanism for fans.

The primary object of the present invention is to provide a manually operated fan in which the mechanism for fans which may be readily mounted upon the table or other support with the operating rod projecting beneath the table and connected with a pedal for operating the fan.

A further object of the invention is to provide a foot actuated fan operating mechanism in which the frame carrying the fan and a portion of the driving mechanism is shiftable relative to the support therefor so that when the same is elevated rotary adjustments may be made, and which frame is held in locked position when lowered to operative position.

With these general objects in view and others that will appear as the nature of the invention is better understood, the same consists in the novel combination and arrangement of parts hereinafter fully described, illustrated in the accompanying drawings and then claimed.

In the drawings forming a part of this application and in which like designating characters refer to corresponding parts throughout the several views: Figure 1 is a side elevational view of a fan operating mechanism built in accordance with the present invention and partially shown in section. Fig. 2 is an end elevational view of the same. Fig. 3 is a top plan view. Fig.

4 is a detail sectional view showing the fan supporting frame elevated with the driven pinions carried thereby out of engagement with the driving gear. Fig. 5 is an enlarged detail sectional view of a portion of the driving mechanism detached. Fig. 6 is a detail view of a portion of a reciprocating rack bar, the driven gear and the pawl and ratchet mechanism for preventing retrograde movement. Fig. 7 includes detail sectional views of the supporting standard for

55 the fan supporting frame showing the man-

ner of locking and unlocking the frame to the standard.

Referring more in detail to the accompanying drawings, the reference numeral 10 designates a base support that may be of any desired configuration and is preferably constructed to enable the same to be mounted upon a table top or other support 11. The bottom 12 of the base support 10 is preferably constructed as more clearly shown in Figs. 1 and 5 and includes spaced vertical standards 13 having the shaft 14 journaled in the upper ends of the standards with enlarged heads at opposite ends thereof to prevent longitudinal movement. A gear 15 is loosely journaled on said shaft and, as shown in Figs. 5 and 6, carries a laterally projecting pivoted pawl 16 spring-pressed as at 17, which pawl is adapted to engage with the ratchet wheel 18 keyed upon the shaft 14 as clearly shown in Fig. 6. A collar 19 holds the ratchet wheel and gear 18 and 15 in spaced relation as indicated. These parts are arranged between two of the vertical standards 13 and arranged between the central standard and the other end standard is the beveled pinion 20 keyed to the shaft 14 and held in spaced relation relative to the standards by collars 19. The base bottom 12 and the table top 11 have alined openings 21 through which projects the rack bar 22 which is in engagement with the gear 15 as is indicated in Figs. 2 and 6, there being provided a collar 23 that is adjustable upon the rack and adapted to engage the bottom of the table top 11 to limit the upward movement of the rack bar. The lower end of the rack bar 22 is connected to the pedal 24 that is tensioned as at 25 so that the rack bar 22 is normally held in its uppermost position.

A vertical standard 26 is supported by the base member 10 and is held immovable relative thereto and journaled on the vertical standard 26 is a driving gear 27 having lower level teeth 28 and upper crown teeth 29, while an upstanding central tubular boss 30 is carried by the driving gear 27 for purposes presently to appear.

The fan supporting frame is loosely mounted upon the vertical standard 26 and is adapted to be held immovable relative thereto by devices later to be described. The fan supporting frame is preferably rectangular in side elevation and includes ver-

tical side bars 31 and 32 and upper horizontal shaft 33 and lower horizontal bar 34, while a central rod 35 connects the upper and lower cross bars. A portion of the mechanism for operating the fan is carried by the fan carrying frame and includes a pair of gears 36 and 36' journaled on stub shafts carried by the side bar 32 and the arm 37 formed on the bottom rail 34. A sprocket chain 38 connects the bearing shaft of the upper gear 36 with the shaft 39 journaled in the side bar 32 and the central rod 35 as is clearly shown in Fig. 1. A gear 40 is keyed to the shaft 39 and is in mesh with the pinion 41 keyed upon the shaft 33. An enlarged gear 42 is fixed to the shaft 33 and is in mesh with the pinion 43 fixed upon the fan shaft 44 that is journaled in the central rod 35 and the side bar 31. The fan shaft 44 extends through the side bar and carries on the projecting end thereof the fan wheel 45.

The lower end of the central rod 35 is made tubular as is shown in Figs. 1 and 7 so that the vertical standard 26 is received in the tubular portion thereof for supporting the fan carrying frame and in the position shown in Fig. 1 the lower bar 34 rests upon the tubular boss extension 30 on the driving gear 27, and in this position the lower gear wheel 36' is in mesh with the teeth 29 upon the driving gear 27, it being noted that the beveled pinion 20 on the drive shaft 14 is in mesh with the lower teeth 28 upon the said gear. When the fan carrying frame is in the position shown in Fig. 1 the spring latch 46 carried by the central rod 35 has the free end thereof projecting into a selected opening 47 formed in the vertical standard 26 which will prevent relative movement of the fan carrying frame and base support 10. When it is desired to change the direction of air current, the fan carrying frame is elevated by the hand hold 48 which will cause the spring latch 46 to be automatically disengaged from the openings 47 and moved to the position shown in Figs. 4 and 7, and in which position the fan carrying frame may be moved to the desired angle as is well understood.

In the operation of the device, it being understood that the base support is preferably mounted upon a table top, the operator may reciprocate the rack bar 22 by pressing on the tensioned pedal 24 with the foot which will cause the gear 15 to be revolved, and such movement communicated to the driving shaft 14 by the tensioned pawl 16 carried by the said gear which is in mesh with the ratchet wheel 18 fixed upon the said shaft. The shaft and beveled pinion are simultaneously revolved and the said

pinion being in mesh with the teeth 28 upon the driving gear will cause the gear to be revolved and such motion communicated to 65 the meshing pinions 36 and through the remaining driving mechanism carried by the fan supporting frame, to the fan shaft 44. The pawl and ratchet mechanism shown in Figs. 5 and 6 will prevent retrograde movement of the shaft 14 and the pinion 20 and the same may be continuously revolved in one direction by repeated reciprocations of the rack bar 22.

From the above detailed description of 75 the construction and operation of the invention, it is thought that the same will be readily understood, and while I have shown and described the preferred embodiment of the present invention, I do not wish to confine myself to the exact details of construction shown, as various forms, modifications and arrangements of the parts as shown may be had without departing from the spirit and scope of the invention as claimed. 85

What I claim as new is:—

1. Driving mechanism comprising a base support, vertical standards carried thereby, a power shaft journaled in said standards, a gear loose on said shaft, a ratchet fixed to 90 said shaft, a tensioned pawl carried by said gear adapted to engage said ratchet, a beveled pinion fixed to said shaft, a central standard fixed to said base support, a driving gear journaled on said standard, lower beveled teeth carried thereby in engagement with said pinion, a frame mounted on said central standard, means for holding said frame immovable relative to the standard, a pair of meshing pinions journaled in said 100 frame and in mesh with said driving gear, meshing gearing carried by said frame and in communication with said meshing pinions, a shaft driven by said gearing, and a reciprocating rack bar in engagement with 105 the loose gear on the driving shaft.

2. Driving mechanism comprising a base support, a vertical standard carried thereby, a horizontal gear journaled on said standard, a driving pinion in mesh with said gear, pawl and ratchet mechanism for driving said pinion, a reciprocating rack bar associated with the pawl and ratchet mechanism, a supporting frame mounted on said standard, a driven member carried by the 110 frame, said standard having circularly arranged openings therein, a spring catch carried by said spring adapted to enter said openings to prevent relative movement between the frame and standard, and driving 115 mechanism for connecting the driven member to the horizontal gear.

In testimony whereof I affix my signature.
DANIEL DOLHAY.
